SOCKET FOR FLUORESCENT LAMPS

Edwin G. Gaynor, Fairfield, Conn.

Application June 20, 1946; Serial No. 677,960

7 Claims. (Cl. 173—328)

1

This invention relates to new and useful improvements in fluorescent lighting equipment and has particular relation to an improved socket for fluorescent lamps.

The objects and advantages of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

In the drawing:

Fig. 1 is a front elevational view showing the socket of the invention;

Fig. 2 is a rear elevational view thereof;

Fig. 3 is a view similar to Fig. 1 but suggesting the manner in which a contact element may be mounted or removed;

Fig. 4 is a sectional view taken inwardly of but parallel to the face of the socket;

Fig. 5 is a bottom plan view of the socket;

Fig. 6 is a central horizontal sectional view through the socket showing the same attached to a support, as, for example, a portion of a reflector; and

Fig. 7 is a view similar to Fig. 1 but showing the contact pins of a fluorescent lamp positioned in the socket.

Referring in detail to the drawings, at 10 is generally indicated the improved one-piece socket and the same is of a molded construction of some resilient or yielding material. Preferably, the socket 10 is molded of artificial rubber or synthetic elastomer of a type capable of withstanding relatively high temperatures. As shown, socket 10 comprises a body 11 in the form of a relatively thick disc having a flat face 12 and having its back 13 flat with the exception that the same carries a small protuberance 14, the purpose of which will appear. Also, opening through the back of the body is a small recess 15 for the reception of an anchoring screw 16.

Within the body 11 is a pair of spaced chambers 16 and 17, such chambers being separated by a relatively thick resilient wall portion 18. A pair of lamp terminal entrance slots 19 and 20 open through the front face 12 and the lower edge of the body 11 and inwardly of such edge these slots also enter the respective chambers 16 and 17. As will be clear from the drawing, the chambers extend inwardly beyond the ends of slots 19 and 20 and further these chambers extend laterally

2

of the slots and toward one another whereby inwardly facing shoulders 21 and 22 are formed at the lower or outer ends of the chamber portions laterally of the entrance slots.

Extending from the inner ends of the chambers are openings or passages 23 and 24 through which conductors 25 and 26 are threaded whereby the conductors pass out of the body 11 through the edge thereof opposite that through which the entrances 19 and 20 open. Within the chambers 16 and 17 are similar but oppositely arranged contact elements, generally designated 27 and 28. Such elements are preferably made of a spring metal and each comprises a short connector arm 29 and an elongated contact arm 30 disposed at an acute angle to the connector arm. Intermediate their ends the contact arms are offset to provide shoulder-like portions 31 adapted to enter partly under lamp terminal pins when the socket of the invention is in use.

The length of each connector arm 29 is preferably slightly greater than the width of the inner end portion of the respective chambers 16 and 17 whereby the free ends of said connector arms enter slightly into the inner portion of the separating wall 18, as at 32, and the bends 33 of the elements at the juncture of the arms thereof, also seat themselves in the resilient material of the body at the outer sides of the chambers.

When the contact elements are fully home their connector arms 29 are against the inner ends of the chambers and it is to such arms that the conductors 25 and 26 are connected in any suitable manner. At this time, the elongated contact arms 30 of the elements extend diagonally downwardly and across the chambers 16 and 17 and the terminal pin entrance slots 19 and 20 and have their free ends disposed over the shoulders 21 and 22 and against or approximately against the dividing wall 18. The location of the shoulders 31 along the length of the contact arms 30 is such that said shoulders are exposed through the entrance slots.

Fig. 3 suggests the manner in which the complete socket of the invention may be assembled and disassembled. The conductors being connected with the arms 29, such conductors are threaded through the entrance slots, the chambers, and the openings 23 and 24, as suggested by the conductor 26 in Fig. 3. Then, the entire body 11 being of resilient material, an outer wall portion thereof is stretched or deflected outwardly as suggested by the broken lines 34 and the contact 28 moved through the relatively narrow entrance slot 20 into the chamber 17. The contact

may be pushed into place until its free end is within the body or it may be moved to final position by pulling on the conductor 26. As the contact is moved into position the bringing of its arm 29 against the inner end wall of the chamber insures that the free end 35 of the contact arm 30 of the element will be shifted to a position inwardly of the shoulder 22 and against or approximately against the lower portion of the dividing wall 18.

The assembled socket is adapted to be mounted on any suitable support, as for example, on a reflector or the like, a portion of which is suggested at 36 in Fig. 6. Preferably, an opening is provided in such reflector portion for the reception of protuberance 14 and also a second opening 37 is provided through which the mounting screw 16 may pass. With the protuberance 14 in one opening of the support, the center mounting screw will hold the socket against the support and the two points of connection will insure the socket remaining in proper alignment and hold it against turning movement about the screw. Clearly, in place of the protuberance 14 the body 11 may have a recess to accommodate a protuberance or lug formed on the support 36.

When the socket of the invention is in use it is merely necessary to insert the terminals 38 of a lamp (not shown) into the entrance slots 19 and 20 and then to shift the lamp to carry such terminals longitudinally of said slots. As this movement occurs, said lamp terminals engage the outer sides of the contact arms 30 of the elements 27 and 28, and tend to force said arms toward one another. When the terminals are fully home they are over the shoulders 31 (see Fig. 7).

There is no danger of the terminals being released since the free end portions of the contact arms are forced against the resilient dividing wall portion 18 of the socket body and thus the resilient body itself maintains a tension on the contact arms 30 of the elements when such arms are in engagement with the lamp terminals 38. Thus the resiliency of the body is an advantage, not only when assembling the contacts in the body, but also at all times during which the contacts are engaged by the terminal pins of the lamp. The resilient body is attempting to expand to normal and maintains a constant tension on the arms and a constant pressure by the arms outwardly against the lamp terminals.

The free ends 35 of the contact arms being disposed over the shoulders 21 and 22, it will be apparent that movement of the lamp terminals 38 downwardly to withdraw them from the socket, or in the direction of the length of the entrance slots, will not result in movement or dislocation of the contact elements. This resistance to casual displacement is assisted by the connector arms 29 of the elements and their position with respect to the end walls of the chambers.

However, if for any reason it is desirable to remove one of the contacts from the socket, an outer wall of the socket may be deformed, as suggested by the broken lines in Fig. 3, and the free end 35 of the contact arm of such element moved outwardly off its shoulder and then the entire element withdrawn from the body, as to the position of element 28 in Fig. 3. Thus the resilient body is useful in the assembly of the present socket and in the dis-assembly thereof, should it become necessary to equip the same with new conductors or the like.

Having thus set forth the nature of my invention, what I claim is:

1. In a fluorescent lamp socket, a resilient one-piece body having a pair of contact pin receiving entrances opening through an edge and a side thereof, said entrances in the form of parallel slots where they open through said side and extend inwardly from said edge, said body having a pair of chambers therein spaced and separated by a portion of the body and communicating one with each of said entrances, said chambers extending in said body beyond the inner ends of said entrances and laterally of said entrances toward one another but inwardly of said edge whereby inwardly facing shoulders are formed, said body having passages for lead wires extending from the inner ends of the respective chambers out through the edge of the body opposite the edge through which the entrances open, a contact element in each of said chambers and each comprising a connector arm disposed against the inner end of its chamber and a substantially diagonal piece extending from the outer end of the connector arm and having its free end above said shoulder whereby the latter prevents casual movement of the contact element out of the chamber, each of said diagonal portions partly exposed in said slot-like portions of the respective entrances and in such portions adapted to be engaged on their outer sides by the contact pins of a fluorescent lamp and pressed toward one another whereby their free ends are pressed against said dividing part of the resilient body and the resiliency of said part assists in putting a continual tension on the contacts while they are engaged by the terminals of the lamp, and said diagonal pieces depressed toward one another in said exposed portions thereby providing shoulders partly overlapping the lamp terminals when the latter are fully home.
2. In a lamp socket, a body having a pair of spaced chambers therein separated by resilient wall portions, means providing inwardly facing shoulders at the respective sides of said wall, a contact in each of said chambers, said contacts each including an arm supported at one end against an outer side wall of the chamber and an elongated arm, spaced lamp terminal entrance slots opening through the front wall of the body into the respective chambers and extending substantially in the direction of the length of the elongated arms, each of said elongated arms extending diagonally across an entrance slot with its free end positioned above one of said shoulders and to engage and be forced against said resilient wall portions when engaged on their outer sides by lamp terminals whereby such wall portions assist in tensioning said arms while the latter are engaged by said lamp terminals, and said elongated arms depressed toward one another intermediate their ends thereby providing shoulders partly overlapping the lamp terminals when the latter are moved fully home.

3. In a lamp socket, a resilient body having a pair of spaced chambers therein, a contact in each of said chambers, said contacts each including an arm disposed against an upper wall of a chamber and extending across the latter and engaging the opposite side walls of the chamber, each of said contacts also including an elongated arm in angular relation to said arm and connected with the outer end thereof, spaced lamp terminal entrance slots opening through the front wall of said body into the respective chambers and extending substantially in the direction of the

length of said elongated arms, means providing an inwardly faced shoulder at each side of the resilient body portion portion between said chambers, each of said elongated arms extending diagonally across an entrance slot with its free end positioned above one of said shoulders and to engage and be forced against the portion of the resilient body between said chambers when said arms are located between and engaged on their outer sides by lamp terminals whereby such body portions assist in tensioning said arms while the latter are engaged by said lamp terminals, and said elongated arms depressed toward one another intermediate their ends thereby providing shoulders partly overlapping the lamp terminals when the latter are moved fully home.

4. In a lamp socket, a resilient body having a pair of spaced chambers therein, a contact in each of said chambers, said contacts each including an arm disposed against an upper wall of a chamber and extending across the chamber and engaging the opposite side walls of the latter, each of said contacts also including an elongated arm in angular relation to said arm and connected with the outer end thereof, spaced lamp terminal entrance slots opening through the front wall of said body into the respective chambers and extending substantially in the direction of the length of said elongated arms, means providing an inwardly facing shoulder at each side of the resilient body portion between said chambers, each of said elongated arms extending diagonally across an entrance slot with its free end positioned above one of said shoulders and to engage and be forced against the portion of the resilient body between said chambers when said arms are located between and engaged on their outer sides by lamp terminals whereby such body portions assist in tensioning said arms while the latter are engaged by said lamp terminals, and said diagonally disposed arms having transversely deflected portions providing shoulders partly overlapping the lamp terminals when the latter are moved fully home.

5. In a lamp socket, a one-piece resilient body having a pair of spaced chambers therein, a contact in each of said chambers, said contacts each including a connector arm and an elongated contact arm to be engaged by a lamp terminal, spaced lamp terminal entrance slots opening through the front wall of the body into the respective chambers and extending substantially in the direction of the lengths of the respective elongated contact arms, each of said contacts having its arms at an acute angle to one another with its connector arm against the inner end wall of its chamber and its elongated arm extending diagonally across its entrance slot with its free end against the body portion spacing said chambers, and said elongated arms depressed toward one another intermediate their ends thereby providing shoul-

ders partly overlapping the lamp terminals when the latter are moved fully home.

6. In a lamp socket, a one-piece resilient body having a pair of spaced elongated chambers therein and spaced lamp terminal entrance slots extending lengthwise of and entering said chambers, shoulders at the outer ends of the walls of said chambers, a pair of contact elements arranged one in each of said chambers and each comprising a pair of arms at an acute angle to one another, said arms of the elements each including a relatively short and a relatively long arm and arranged with their short arms against the inner ends of the respective chambers and their long arms each extending diagonally across its entrance slot with its free end toward the body portion spacing the chambers and over the shoulders in said chambers whereby the elements are resiliently tensioned on being pressed against said body portion by lamp terminals and are held in place and may not be casually moved out through the ends of said chambers, and said long arms of said elements depressed toward one another intermediate their ends thereby providing shoulders partly overlapping the lamp terminals when the latter are moved fully home.

7. In a lamp socket, a one-piece resilient body having a pair of spaced elongated chambers therein and spaced lamp terminal entrance slots extending lengthwise of and entering said chambers, shoulders at the outer ends of the walls of said chambers, a pair of contact elements arranged one in each of said chambers and each comprising a pair of arms at an acute angle to one another, said arms of the elements each including a relatively short and a relatively long arm and arranged with their short arms against the inner ends of the respective chambers and their long arms extending diagonally across its entrance slot with its free end over the shoulders in said chambers whereby the elements are held in place and may not be casually moved out through the ends of said chambers, and said long arms of said contact elements depressed toward one another intermediate their ends thereby providing shoulders partly overlapping the lamp terminals when the latter are moved fully home.

EDWIN G. GAYNOR.
